UNITED STATES PATENT OFFICE.

THEODORE P. DRIVER, OF MELROSE, MASSACHUSETTS.

AUTOMOBILE-LAMP.

1,077,192.

Specification of Letters Patent.

Patented Oct. 28, 1913.

Application filed November 7, 1912. Serial No. 729,944.

To all whom it may concern:

Be it known that I, THEODORE PRESCOTT DRIVER, a citizen of the United States, residing at Melrose, in the county of Middlesex and State of Massachusetts, have invented new and useful Improvements in Automobile-Lamps, of which the following is a specification.

My invention relates to electric lamps for use in automobiles and for similar purposes.

The object of my invention is to provide a lamp to be operated by a dry battery, and one that is easily accessible to the operator and is economical to construct.

15 In the accompanying drawing illustrating my invention, Figure 1 is a perspective view of my invention. Fig. 2 is a vertical section of Fig. 1 through the line A—A. Fig. 3 is an edge view of the dash-board of an automobile, having one of my lamps installed therein. Fig. 4 is a plan view of the inside of the cap of the receptacle. Fig. 5 is a plan view of the inside of the cap with certain parts removed.

25 Similar numerals indicate corresponding parts in all the figures of the drawing.

Referring to the drawing, 6 represents a receptacle made of gutta-percha, fiber or other suitable material, cylindrical in form, 30 and composed of the main portion 7 and the cap 8.

9 is the lens of the receptacle, which is prevented from displacement by the hemispherical shaped metallic reflector 10 containing an incandescent lamp 11 operated by a dry battery, with which it is connected by the conductors 12 and 13. The cap 8 of the receptacle has a circular recess 14 formed on the inside surface.

40 15 is a disk made of wood, fiber or any other suitable insulating material, having a V-shaped notch 16 cut therein. The conductor 13 is connected with a flat spring 17 which forms one pole of the battery, and

45 with which the switch 18 makes and breaks contact. The conductor 12 is connected with a spring metallic upright piece 19, which forms the opposite pole of the battery. The switch 18 consists of a banjo shaped resilient piece of copper, the body of which fits loosely in the circular recess 14 of the cap 8, when not in contact with the pole piece 17. The body of the switch 18 is confined in the recess 14 by the disk 15, and the neck of the 55 switch lies in a shallow recess 20 in the sur-

face of the cap 8 to a depth about equal to the thickness of the material of which the switch 18 is formed. The switch rests on the edge 29 of the recesses 14 and 20, which thus serves as a fulcrum. The neck of the 60 switch is kinked at 26 thus bringing the body closer to the disk 15. The pole piece 17 formed of resilient material is bent downwardly through the notch 16, and bears upon the surface of the cap 8 in the recess 20, 65 forming a spring, so that when the switch 18 is forced beneath the pole piece 17, the pole piece holds the body of the switch 18 against the underside of the disk 15 with yielding pressure. The pole pieces 17 and 70 19 and the disk 15 are secured to the cap 8 by the screws 21, which also serve to confine the conductors and connect them with the pole pieces 17 and 19.

When the parts are assembled, the cap is 75 secured to the receptacle by bolts 22, extending through the flange 23. The base 24 of the lamp will then extend through the central opening 25 in the disk 15 and contact with the body of the switch 18 will result 80 when the latter is forced under the pole piece 17. The yielding pressure of the switch 18 will always insure contact of the switch with the base 24 when the switch is thus confined by the pole piece 17. The upright 85 pole piece 19 rests in contact with the metallic reflector 10 with a yielding pressure, thereby forming a circuit through the lamp. I construct the receptacle in the form of a cylindrical box 6 with the flange 23 for the purpose of having the lens of the receptacle 90 protrude outside the dash-board, and having the flange 23 rest against the inside of the dash-board, and rendering the switch readily accessible to the operator within the car. Two of these lamps may be installed in the dash-board of the car and connected with a dry battery in series, and so installed that both lamps may be thrown into and out of 95 circuit by the switch of either lamp. 100

I find that two lamps of the character described and installed in the dash-board will provide the necessary head lights, when the large head lights are out of order or fail for any reason, and that they will always 105 enable the operator to extinguish the large head lights when the car is standing in a public place, thereby saving the expense incident to running the latter at such time.

The construction of my lamp is exceed- 110

2
ingly simple and economical, and the application of it to the dash-board of an automobile is convenient and inexpensive. It also furnishes a suitable light at a very slight expense.

5 It is obvious that a lamp of the construction described is useful in many places, such as for the purpose of lighting the interior or exterior of automobiles, and sailing lights for motor boats.

10 What I claim and desire to secure by Letters Patent is:

1. In a receptacle containing an electric lamp, the combination of a cap provided with a recess, a switch loosely contained in said recess and adapted to bear against the edge of the recess as a fulcrum, and a spring adapted to press on said switch and establish contact between said switch and the base 20 of the lamp.

2. In a receptacle containing an electric lamp, the combination of a cap provided with a recess, a switch loosely fitting said recess, a disk of insulating material adapted 25 to confine said switch in said recess, said disk having an opening adapted to permit contact between the base of the lamp and the body of the switch, and a spring adapted to establish such contact.

30 3. In a receptacle containing an electric lamp, the combination of a cylindrical main portion provided with an annular flange at one end, a cap provided with a recess adapted to be secured thereto, a switch loosely contained in said recess, and a spring adapted to establish contact between said switch and the base of the lamp, said main portion being adapted to extend through the dash board of a vehicle, and the flange adapted to 40 be located on the inside of the dash board.

4. In an electric lamp holder, the combination of a cap of insulating material having a central circular recess on its inner face, and a radial V-shaped notch extending from 45 said recess to the circumference of the cap, a plate of insulating material adapted to be fastened to the inner face of the cap and provided with an opening registering with the recess in the cap, a banjo-shaped switch 50 lying in said recess and V-shaped notch, and contact means carried on the exterior of the plate but overhanging the edge thereof and adapted to rest on the extremity of the switch when the latter is in one position in

the V-shaped notch, but clearing the switch 55 when it is in other positions therein.

5. In an electric lamp holder the combination of a cap of insulating material having a central circular recess on its inner face, and a radial V-shaped notch extending from 60 said recess to the circumference of the cap, a plate of insulating material adapted to be fastened to the inner face of the cap and provided with an opening registering with the recess in the cap, a banjo-shaped switch 65 lying in said recess and V-shaped notch, and contact means carried on the exterior of the plate but overhanging the edge thereof and adapted to rest on the extremity of the switch when in one position in the V-shaped 70 notch, but clearing the same when in other positions therein, together with a metal reflector, provided with a central opening adapted to receive and make contact with the side of a lamp base, means for holding 75 said reflector in front of the plate with said opening concentric with the plate opening, and electric conductors connected one to the above mentioned contact means, and the other to the reflector.

80 6. In an electric lamp holder, the combination of a cap of insulating material having a central circular recess on its inner face, and a radial V-shaped notch extending from 85 said recess to the circumference of the cap, a plate of insulating material adapted to be fastened to the inner face of the cap and provided with an opening registering with the recess in the cap, a switch lying in said 90 recess and V-shaped notch, and contact means carried on the exterior of the plate but overhanging the edge thereof and adapted to rest on the extremity of the switch when in one position in the V-shaped notch, but clearing the same when in other 95 positions therein, together with means for holding an incandescent lamp in front of said plate with its base projecting through the opening therein and in contact with the switch.

100 In testimony whereof I have hereunto set my hand in presence of two subscribing witnesses, this 17th day of October, 1912.

THEODORE P. DRIVER.
